UNITED STATES PATENT OFFICE

143,351

DESIGN FOR AN AIRPLANE OR SIMILAR ARTICLE

Peter Porcelli, New York, N. Y., assignor to Anna
Marzullo, New York, N. Y.

Application September 15, 1944, Serial No. 115,308

Term of patent 3½ years

(Cl. D71—1)

To all whom it may concern:

Be it known that I, Peter Porcelli, a citizen of the United States, residing at Bronx, New York city, New York, have invented a new, original, and ornamental Design for an Airplane or Similar Article, of which the following is a specification, reference being had to the accompanying drawings, forming a part thereof.

Figure 1 is a top plan view of an airplane, showing my new design.

Figure 2 is a side elevational view,
Figure 3 is a rear elevational view; and
Figure 4 is a bottom plan view thereof.

I claim:

The ornamental design for an airplane or similar article, as shown.

PETER PORCELLI.
